(57) **CLAIM**

The ornamental design for a storage container as shown and described.

DESCRIPTION

FIG. 1 is a top front right isometric view of a storage container showing my new design.

FIG. 2 is a top rear isometric view thereof;

FIG. 3 is a top front isometric view thereof;

FIG. 4 is a top view thereof;

FIG. 5 is a first side view thereof;

FIG. 6 is a second side view thereof;

FIG. 7 is a bottom view thereof;

FIG. 8 is a front view thereof; and,

FIG. 9 is a rear view thereof.

The broken lines illustrate portions of the storage container that form no part of the claimed design.
